CHAIR CONSTRUCTION

George D. Schermerhorn, Reading, Mich.

Application October 30, 1933, Serial No. 695,727

1 Claim. (Cl. 155—142)

My invention relates to improvements in chair construction and particularly to chairs of the type which are used as bridge chairs or folding chairs adapted for intermittent use.

5 It pertains primarily to that type of chair structure wherein there is employed a U-shaped frame section which, as here illustrated, may be formed of a bent wood frame and wherein there is provided a bowed back rest. The back rest is 10 here also illustrated as being of bent wood construction. This general type of construction is very old.

15 My improvement has to do with the provision of means which prevents the back rest portion from becoming disengaged at either end from the frame due either to spreading apart of the frame members or to flexing of the back rest portion itself, and farther to the provision of means which will maintain the provided curvature of the back rest portion and protect the lower edge against breakage.

20 My improvement renders the chair structure more stable and sturdy and is simple and inexpensive.

25 Other objects and advantages of my improved construction will more fully appear from the following description, appended claim, and accompanying drawing, wherein:

30 Fig. 1 is a side elevation, partly in section, of a chair embodying my invention,

Fig. 2 is a front elevation of the upper end of the frame and back rest structure, partly in section, showing my improvement,

35 Fig. 3 is a vertical sectional view taken on line 3—3 of Fig. 2, and

Fig. 4 is a horizontal sectional fragmentary view taken on the line 4—4 of Fig. 2.

40 My improved chair comprises a bent wood frame 10 which constitutes the two front legs of the chair and the support for the seat and back rest. Rear legs 12 are provided which are pivoted at their upper ends to the frame 10 by the pivots 18. A seat 16 is pivoted at 14 between the uprights of the U-frame 10. The rear end of the seat is provided with gudgeons 20 which ride in a slot 22 formed in the rear legs.

45 My invention is related primarily to the back rest construction and the back rest proper is 50 shown as consisting of a bent wood back rest portion 24. The ends of this bowed back rest are received within grooves 26 formed in the

U-frame. To this extent the construction is standard.

I have provided, however, means in the form of a tie rod 28, the ends of which are received within deepened recesses 30 of the grooves 26 and secured to the legs of the frame 10 by rivets 32. This tie rod 28 is a metal strap bowed to conform to the provided curvature of the bowed back rest 24 and the intermediate portion of it is secured by rivet 34 to the intermediate portion of the back rest 24. The strap itself extends along the rear face of the back rest adjacent the lower edge as shown in the drawing.

10 This strap holds the legs of the U-frame 10 together against spreading and also by virtue 15 of its connection with the back rest holds the back rest against flexing, thereby preventing the back rest from becoming disengaged at either end from the U-frame. This strap is sufficiently flexible, however, to permit required flexing of 20 the back rest without permitting the same to become disconnected from the U-frame. This strap also holds the back rest from falling downwardly from its point of connection with the U-frame and holds the back panel to the curve 25 to which it has been bent and protects the lower edge of the panel from breakage.

What I claim is:

30 A chair structure comprising, in combination, a U-shaped chair frame provided with grooves 30 formed on the inner faces of the two legs of the U-shaped frame adjacent to the closed end thereof, a bowed back rest panel extending across the closed end of the U-shaped frame between the legs thereof and having its ends 35 freely seated within the grooves of the frame but not secured directly thereto, said frame provided with a recess in the lower end of each groove at the back thereof extending into the frame to a greater depth than the groove, a flexible metal reinforcing strip extending along the back of the panel and bowed to conform therewith having its ends extending into said recesses beyond the ends of the panel and secured beyond the ends of the panel to the frame forming a 40 tie rod between the two legs of the U-shaped frame preventing the spreading of said legs, said strip being secured to the panel intermediate its ends preventing flexing thereof sufficiently to withdraw the ends of the panel from 45 the groove in the frame.

GEORGE D. SCHERMERHORN.
